UNITED STATES PATENT OFFICE.

CHARLES K. VOLCKENING, OF NEW YORK, N. Y.

BOTTLE-WASHING MACHINE.

1,034,938.

Specification of Letters Patent.

Patented Aug. 6, 1912.

Application filed June 13, 1911. Serial No. 632,823.

To all whom it may concern:

Be it known that I, CHARLES K. VOLCKENING, a citizen of the United States, and a resident of the city and State of New York, 5 have invented certain Improvements in Bottle-Washing Machines, of which the following is a specification.

This invention relates to certain improvements in bottle washing machines, and more 10 particularly in that class or type of such machines wherein a stationary mouth piece or nipple is provided for engagement with the mouth or lip of the bottle during the operation of the washing devices, and the object of the invention is to provide a machine 15 of this general character having means for actuating or supporting the washing devices adapted for coöperation with such mouth piece or nipple in an improved manner during the use of the machine, and presenting certain features of novelty and advantage, whereby increased durability is attained, and repairs may be effected in a quick and convenient manner.

20 The invention consists in certain novel features of the construction, and combinations and arrangements of the several parts of the bottle washing machine, whereby certain important advantages are attained, 25 and the machine is rendered simpler, less expensive in structure and operation, and otherwise better adapted and more convenient and effective for use, all as will be hereinafter fully set forth.

30 The novel features of the invention will be carefully defined in the claims.

In order that my improvements may be the better understood, I will now proceed to describe the invention with reference to the 35 accompanying drawings, wherein—

Figure 1 is an axial section taken through the mouth piece or nipple and actuating or supporting means for the washing devices of a bottle washing machine, and illustrating 40 one embodiment of my invention; Fig. 2 is a detail view illustrating in plan certain features of the anti-friction bearing at the upper end or head of the supporting sleeve or member, Fig. 3 is a transverse section 45 taken through the actuating and supporting means in the plane indicated by the line $a-a$ in Fig. 1, illustrating certain features of the guiding means comprised in my present invention; Fig. 4 is a detached and

enlarged perspective view illustrating certain features of the construction of the feather forming part of the guiding means illustrated in Figs. 1 and 3; Fig. 5 is a fragmentary sectional view taken axially through the lower end of the supporting sleeve or member in a plane at right angles to the plane of the section in Fig. 1, and showing certain features of the guiding means to be hereinafter explained; Fig. 6 is a fragmentary sectional view taken axially through the anti-friction devices at the upper end or head of the supporting sleeve or member and illustrating a slightly different formation of such devices comprised within my present invention; Fig. 7 is a view somewhat similar to Fig. 2, illustrating another slightly different structure of the anti-friction devices at the head end of the supporting member, and Fig. 8 is another fragmentary sectional view somewhat similar to Fig. 6, illustrating still another different formation of the anti-friction devices comprised in my present invention.

In these views I have not deemed it essential to illustrate the detailed construction of the bottle washing machine to which my improvements are applied for use, excepting as to such of the operative parts with which my improvements are directly concerned or related, and I desire it to be understood that the invention is not limited in its application to any special kind or style of bottle washing machine, but may be applied to machines of various constructions with good results, in which case it will 80 obviously be within the range of the invention to modify or vary the formation and arrangement of the operative parts to accommodate the particular machine to which my improvements are to be applied.

The machine wherein my improvements are herein shown embodied is provided with a stationary mouth piece or nipple with which the mouth or lip of the bottle is adapted to be engaged during the washing 100 operation, in such a manner that the washing devices may be guided in appropriate alignment with the mouth of the bottle for washing the same in a well known way, and such washing devices may be of the usual kind or type, including a longitudinally movable jet pipe or member insertible through the mouth-piece or nipple into the

interior of the bottle and provided with brushes adapted for rotation within the bottle for cleansing the same. As such devices are well known and form no material part of the present invention, I have not considered it necessary to show them in detail herein.

The mouth piece or nipple as herein shown comprises a lower cup-like member or housing 1, within which is arranged an upper flanged member 2 having detachable screw engagement with the lower member as indicated at 3 and provided in its upper surface with a flared or concave seat 4 with which the mouth or lip of the bottle to be washed is adapted to be engaged in a well known way so that a close joint may be produced between the mouth piece or nipple and said lip of the bottle, and said upper member is provided with a central passage, or bore 5 through which the washing devices are adapted to be projected, when moved longitudinally, so as to enter into the mouth of the bottle in a well known way.

The form and proportion of the members 1 and 2 of the mouth piece or nipple as herein shown is such that a space or chamber 6 is produced within the lower member 1 beneath the upper flanged member 2, adapted for the reception of the enlarged or headed upper extremity 7 of the supporting member 8, which is made tubular as shown, being provided with an axial bore or passage to be traversed by the washing devices as indicated at 16, and is adapted for rotatory movement in unison with such washing devices. The lower part of the member 1 of the mouth piece or nipple is provided with an inturned annular flange, as indicated at 7^a, which by engagement beneath the head or enlargement 7 of the supporting member 8, effectively supports the said member 8 in position pendent from the mouth piece, and affords a bearing wherein said headed upper end of such member 8 turns during its rotatory movement.

At its lower part, the supporting member 8 suspended from the mouth piece or nipple, as above described, is provided with longitudinally extended guiding devices 9, 9, diametrically opposite to one another, and forming features projecting from the diametrically opposite sides of said member for engagement in correspondingly located grooves or ways produced in an actuating sleeve or member 10, which in the usual construction of machines of this type or kind is mounted in a bearing for free rotatory movement and is provided with an annular gear surface, as shown at 11 with which gearing is adapted for engagement in such a manner as to impart rapid rotatory movement to said actuating member, and through the guides or feathers 9, 9, to the inclosed supporting sleeve or member 8, while per-

mitting such endwise movement of the said member 8 within said member 10 and mouth piece member 1 as is required in the operation of the parts to which I have shown my improvements applied for use.

The guiding devices 9, 9 at diametrically opposite sides of the supporting member 8 also operate to guide and direct the endwise movements of the washing devices within said member 8, while compelling rotatory movement of such washing devices in unison with the rotatory movement of the supporting member within whose bore 16 such devices are normally inclosed in the usual manner. In the drawings I have shown one element of the endwise movable washing devices at 34 in Fig. 3, the same being engaged with the guiding devices 9, 9, so as to be capable of the endwise movement requisite to assure introduction into the bottle and at the same time to compel rotation of such washing devices in unison with the sleeve of member 8 and actuating member 10.

In the operation of machines of this general character as heretofore constructed, where integral guides or feathers have been provided inside and outside the lower part of the supporting sleeve or member 8, the strain imposed upon the parts during rotation and relative endwise movement of the members has ordinarily resulted in such great wear of the guiding means as quickly unfit the parts for use, and requires their replacement at short intervals, with consequent expense and interruption of the use of the machine, and to avoid the expense and annoyance hitherto common in such machines, I have provided the member 8 with removable separately formed guiding members 9, 9, diametrically positioned at its lower part, so that when these members become worn during the use of the machine, they may be quickly and conveniently withdrawn and replaced at a minimum of expense and without substantial interruption of the use of the machine.

In the structure herein shown, the wall of the sleeve or member 8 is sawed or cut through at diametrically opposite points, 115 as clearly shown at 12, 12 in the drawings, and the members 9, 9, being made in the form shown in Figs. 1 and 4, are provided with widened portions 14, of such dimensions as to be adapted to fit snugly within 120 the recesses 12, 12, with outer edge portions protruding beyond the peripheral surfaces of the member 8 and affording external feathers for sliding engagement within the grooves of the actuating member 10, and in 125 inner edge portions 15, 15 projecting within the bore 16 of the supporting member for similar sliding engagement with the diametrically opposite grooves or ways of the member 34 of the washing devices during 130

endwise movement of such devices relatively to the supporting member. These replaceable members 9, 9, may be conveniently and inexpensively made from steel or other suitable metal, and for holding them removably in position within the slotted openings 12, 12 of member 8 I have shown pins 20, 20 passed in spaced relation through each such member 9 and through the walls of the member 8, which may be readily driven out and reinserted when the parts of the machine are separated to permit the convenient removal and substitution of the members 9. Above the openings 12, 12, the side walls of the member 8 have grooves or channels in their external surfaces as indicated at 17 in Fig. 1, and the members 9 have narrow upper extensions which fit accurately in these grooves 17, and have pointed extremities 18, which are adapted for engagement in undercut portions at the upper extremities of such grooves to retain said upper extensions in relation to the member 8. At their inner parts, the members 9, 9 are also provided with short upturned extensions or locking portions 19, 19 which engage upon the inner surface of the member 8, above the slotted openings 12, 12 in the side walls thereof and further assist in retaining the members 9 in accurate relation to the sleeve 8, while the lower extremity of said sleeve or member 8, whereat the slots 12, 12 terminate and are open, is made reduced as indicated at 21, for the reception of an externally flanged ferrule 22, which encircles the slotted lower end of said sleeve or member to prevent spreading of the same, and is held in position by means of screws 23, 23 or the like, as indicated in Fig. 5. The lower extremities of the guide members 9, 9 are also shown provided with reduced portions 24, 24 which fit within the flange of the ferrule 22, in order that the said members 9 may be effectively held in place at their lower ends. The ferrule 22 is readily removable and replaceable when it is desired to remove and substitute the guide members 9.

In the parts to which I have herein shown my improvements applied for use, the formation and arrangement of the headed upper end of the supporting sleeve or member and of the chamber 6 of the mouth piece or nipple is such that the upper surface of said headed end of the member 8 is normally below and out of contact with the upper member 2 of the mouth piece, so that as the member 8 turns when in its lowered position, there will be no wearing contact between its headed upper end and the undersurface of said member 2 of the mouth piece, but when in the operation of the machine, the supporting sleeve or member is thrust forcibly upward, the upper surface of its head or enlargement 7 is brought into

contact with the undersurface of the mouth piece member 2 in such a manner as to produce a close joint therewith, whereupon the bore or passage 16 of the member 8 forms a substantial continuation of the opening 5 of the mouth piece in order to guide the washing device, when the same move endwise within member 8, accurately up through the neck of the bottle engaged with said mouth piece.

In such machines as heretofore constructed, the engagement of the headed end of the supporting member with the undersurface of the member 1 of the mouth piece has also resulted in aggravated wear by reason of the rapid rotation of the member 8 in contact with the stationary mouth piece member 2, so that it has been necessary to separate and replace the worn parts at frequent intervals, with resultant interruption of the use of the machine, and expense for new parts, and my invention contemplates the provision of novel means whereby this wear may be materially lessened without material modification of the construction, and whereby such wear as occurs may be readily compensated for by replacement of minor parts at small expense and without material interruption in the use of the machine.

In the embodiment of my invention herein shown, the undersurface 25 of the member 2 of the mouth piece or nipple is made flared or conical, so as to fit accurately upon a correspondingly formed surface 26 at the upper side of the head or enlargement 7 of the supporting sleeve or member 8 for the production of a tight joint between the parts when said member 8 is thrust endwise and upward, and said conical surface 26 is produced upon a separable and independently formed part or member 27 produced from thin metal in inverted cup-like shape, which is supported above an annular integral flange 33 of said member 8 by means of an interposed anti-friction bearing in such a manner that said part or member 27 may turn freely upon the upper end of the supporting sleeve or member. In this manner, when the sleeve or member 8 is thrust upward to force the part or member 27 into forcible and accurate contact upon the undersurface 26 of the member 2 of the mouth piece, the friction exerted upon contact of the conical surfaces of said member 2 and part 27 will be sufficient to hold said part or member 27 securely against turning movement, while the anti-friction bearing between the conical surface 26 of the part or member 27 and the flange 33 of the member 8 will permit free turning movement of said member 8 relatively to the part 27 so that no wear whatever will occur at the contacting surfaces 25 and 26, and such wear as will occur at the anti-friction bear-

ing will be either negligible or may be compensated for by adjustment or replacement of the bearing parts when worn.

I do not desire to be understood as limiting myself to the precise formation and arrangement of the anti-friction bearing provided as above explained between the upper end of the supporting member 8 and the loosely mounted part or member 27 held thereon, since it will be apparent that such bearing may be of various kinds within the scope of the invention. For example, in Figs. 1 and 2 I have shown a form of ball bearing, wherein a series of balls 31 are held within a retaining member or ring 30, which has screw engagement with the upper extremity of the supporting sleeve 8 and is adapted to be locked in adjusted relation thereon by means of a pin or key 32, in such position that its contained balls 31 bear upon a collar or member 29 rested upon the integral flange 33 of the sleeve or member 8, while certain of its balls support the superposed freely rotatable part or member 27, which has a circumferential pendent skirt portion encircling the members 29 and 30 with its lower edge portion swaged inward to afford a means for retaining the said part or member 27 in position upon the supporting member 8, as shown at 28 in the drawings.

In Fig. 6 I have shown another formation of the antifriction bearing within the scope of the present invention, wherein balls 31, in upper and lower series are engaged with a central bearing member 30^a, the lower ball series operating upon a lower bearing member 29, while the upper ball series support the freely rotatable part 27 which is similar in form and arrangement to that shown in Fig. 1.

In Fig. 7 I have illustrated a form of roller bearing which may be used in lieu of the ball bearings above referred to when desired, with good results, wherein a series of rollers 31^a are substituted for the balls in a retainer 30^a, and in Fig. 8 I have illustrated still another formation of the anti-friction bearing comprised within the scope of my present invention, wherein the supporting member 8 is provided with an integral annular bearing member 30^b surrounding its upper end, anti-friction rings or washers 31^b, 31^c being positioned below and above the same to promote the free turning movement of the part or member 27 supported upon the uppermost ring or washer. These anti-friction rings or washers 31^b may be conveniently formed from brass or other soft metal so as to receive the wear in order that repairs may be effected by removal and substitution of such rings or washers.

From the above description it will be apparent that the improved machine constructed according to my invention is of an ex-

tremely simple and comparatively inexpensive nature, and is particularly well adapted for use by reason of the simplicity of its construction, its durability and strength and the facility with which repairs may be effected, and it will also be obvious from the above description that the device is susceptible of considerable modification without material departure from the principles and spirit of the invention, and for this reason I do not desire to be understood as limiting myself to the precise formation and arrangement of the several parts herein set forth in carrying out my invention in practice.

Having thus described my invention, what I claim and desire to secure by Letters Patent is:

1. A device of the character described having two concentric rotatable members, one of which is movable endwise relatively to the other, one such member being a supporting member adapted to be traversed by a washing device, and the other member being an actuating member inclosing said supporting member, a guide removably mounted upon one of said members and engageable with the other member to compel rotation of such members in unison, said guide being provided with an integral projection having interlocking engagement with the member whereon the guide is mounted and disengageable from such member upon endwise movement of the guide relatively to such member, and releasable means for preventing endwise movement of the guide relatively to the member whereon the same is mounted.

2. A device of the character described having two concentric rotatable members, one of which is movable endwise relatively to the other, one such member being a supporting member adapted to be traversed by a washing device, and the other member being an actuating member inclosing said supporting member, a guide removably mounted upon one of said members and engageable with the other member to compel rotation of such members in unison, said guide being provided with a notch affording spaced projections having interlocking engagement with the member whereon the guide is mounted and disengageable from such member upon endwise movement of the guide relatively to such member, and releasable means for preventing endwise movement of the guide relatively to the member whereon the same is mounted.

3. A device of the character described having two concentric rotatable members, one of which is movable endwise relatively to the other, one such member being a supporting member adapted to be traversed by a washing device, and the other member being an actuating member inclosing said supporting member, a guide removably mount-

- ed upon one of said members and engageable with the other member to compel rotation of such members in unison, said guide being provided at one end with an integral 5 projection having interlocking engagement with the member whereon the guide is mounted, and disengageable from such member upon endwise movement of the guide relatively to such member, and a part having screw connection with the member whereon the guide is mounted and having engagement with the opposite end portion of said guide to prevent endwise movement thereof relatively to the member whereon said guide 10 is mounted.
15. A device of the character described having a slotted supporting member, a guide removably inserted in the slot of said member and having inner and outer edge 20 portions projecting from the inner and outer surfaces of the supporting member, and pins passed through said guide and engaged with the walls of the supporting member for retaining said guide removably in 25 place, an actuating member surrounding the supporting member and wherewith the outer edge portion of said guide has sliding engagement and an endwise movable washing device within the supporting member 30 and wherewith the inner edge portion of said guide has sliding engagement.
35. A device of the character described having a supporting member one end portion of which has diametrically opposite slots extended through it and is provided with a reduced extremity, guides removably inserted in the slots at opposite sides of said member and having inner and outer edge portions projecting from the inner and 40 outer surfaces of said member and affording feathers for guiding engagement with coöoperating members, and a ferrule removably applied at the extremity of said supporting member and operable to prevent 45 spreading thereof.
50. A device of the character described having a stationary mouthpiece engageable with the lip of a bottle to be cleansed, a supporting member mounted for rotatory movement and adapted to be traversed by a washing device and capable of endwise movement into and out of coöoperative relation to the mouthpiece, means for rotating said supporting member, and a freely rotatable part interposed between the supporting member and the mouthpiece and adapted to be moved into and out of engagement with the mouthpiece, upon endwise movement of said supporting member, and adapted 55 to be held against movement by such engagement with said mouthpiece.
60. A device of the character described having a stationary mouthpiece engageable with the lip of a bottle to be cleansed, a supporting member mounted for rotatory and endwise movement into and out of coöoperative relation to the mouthpiece, means for rotating said supporting member, and a freely rotatable part interposed between the supporting member and the mouthpiece and adapted to be moved into and out of engagement with the mouthpiece, upon endwise movement of said supporting member, and adapted to be held against movement by such engagement with said mouthpiece.
65. A device of the character described having a stationary mouthpiece engageable with the lip of a bottle to be cleansed, a supporting member mounted for rotatory and endwise movement into and out of coöoperative relation to the mouthpiece, means for rotating said supporting member, and a freely rotatable part interposed between the supporting member and the mouthpiece and adapted to be moved into and out of engagement with the mouthpiece, upon endwise movement of said supporting member, and adapted to be held against movement by such engagement with said mouthpiece.
70. A device of the character described having a mouth piece one side of which is engageable with the lip of a bottle to be cleansed, said mouth piece being stationary during engagement of the bottle therewith, a driven rotatable supporting member movable toward and from the opposite side of the mouth piece and adapted to be traversed by a washing device insertible within the bottle through said mouth piece, and a part interposed between the driven rotatable supporting member and stationary mouth piece normally capable of free movement and adapted upon movement of the supporting 75 member toward the mouth piece, to be pressed into close engagement with said mouth piece to afford a close joint between the same and the supporting member, said interposed part, when engaged with the mouth piece, being held stationary in position to prevent wear thereof.
80. A device of the character described having two members, one of which is a stationary mouth piece engageable with the lip of a bottle to be cleansed, and the other of which is a driven rotatable supporting member movable toward and from the mouth piece and adapted to be traversed by a washing device insertible within the bottle 85 through said mouth piece, and a part interposed between the driven rotatable supporting member and stationary mouth piece normally capable of free movement and adapted upon movement of the supporting member toward the mouth piece, to be pressed into close engagement with said mouth piece to afford a close joint between the same and the supporting member, said interposed part, when engaged with the mouth piece, being held stationary in position to prevent wear thereof.
85. A device of the character described having two members, one of which is a stationary mouth piece engageable with the lip of a bottle to be cleansed, and the other of which is a driven rotatable supporting member movable toward and from the mouth piece and adapted to be traversed by a washing device insertible within the bottle 90 through said mouth piece, and a part interposed between the driven rotatable supporting member and stationary mouth piece normally capable of free movement and adapted upon movement of the supporting member toward the mouth piece, to be pressed into close engagement with said mouth piece to afford a close joint between the same and the supporting member, said interposed part, when engaged with the mouth piece, being held stationary in position to prevent wear thereof.
95. A device of the character described having two members, one of which is a stationary mouth piece engageable with the lip of a bottle to be cleansed, and the other of which is a driven rotatable supporting member movable toward and from the mouth piece and adapted to be traversed by a washing device insertible within the bottle 100 through said mouth piece, and a part interposed between the driven rotatable supporting member and stationary mouth piece normally capable of free movement and adapted upon movement of the supporting member toward the mouth piece, to be pressed into close engagement with said mouth piece to afford a close joint between the same and the supporting member, said interposed part, when engaged with the mouth piece, being held stationary in position to prevent wear thereof.
105. A device of the character described having two members, one of which is a stationary mouth piece engageable with the lip of a bottle to be cleansed, and the other of which is a driven rotatable supporting member movable toward and from the mouth piece and adapted to be traversed by a washing device insertible within the bottle 110 through said mouth piece, and a part interposed between the driven rotatable supporting member and stationary mouth piece normally capable of free movement and adapted upon movement of the supporting member toward the mouth piece, to be pressed into close engagement with said mouth piece to afford a close joint between the same and the supporting member, said interposed part, when engaged with the mouth piece, being held stationary in position to prevent wear thereof.
115. A device of the character described having two members, one of which is a stationary mouth piece engageable with the lip of a bottle to be cleansed, and the other of which is a driven rotatable supporting member movable toward and from the mouth piece and adapted to be traversed by a washing device insertible within the bottle 120 through said mouth piece, and a part interposed between the driven rotatable supporting member and stationary mouth piece normally capable of free movement and adapted upon movement of the supporting member toward the mouth piece, to be pressed into close engagement with said mouth piece to afford a close joint between the same and the supporting member, said interposed part, when engaged with the mouth piece, being held stationary in position to prevent wear thereof.
125. A device of the character described having two members, one of which is a stationary mouth piece engageable with the lip of a bottle to be cleansed, and the other of which is a driven rotatable supporting member movable toward and from the mouth piece and adapted to be traversed by a washing device insertible within the bottle 130 through said mouth piece, and a part interposed between the driven rotatable supporting member and stationary mouth piece normally capable of free movement and adapted upon movement of the supporting member toward the mouth piece, to be pressed into close engagement with said mouth piece to afford a close joint between the same and the supporting member, said interposed part, when engaged with the mouth piece, being held stationary in position to prevent wear thereof.

members and removably connected with one of them, and adapted, upon movement of the supporting member toward the mouth piece, to be moved into and out of engagement with the stationary mouth piece and, when engaged therewith, to reduce wear and prevent frictional contact between said members.

In witness whereof I have hereunto signed my name this 10th day of June 1911, in the presence of two subscribing witnesses.

CHARLES K. VOLCKENING.
